CLAIM

The ornamental design for a skull pan, as shown and described.

DESCRIPTION

FIG. 1 is a first top perspective view of a skull pan according to the present invention.

FIG. 2 is another top perspective view of the skull pan of FIG. 1 rotated 90 degrees in a counter-clockwise direction.

FIG. 3 is a first bottom perspective view of a skull pan of FIG. 1.

FIG. 4 is another bottom perspective view of the skull pan of FIG. 3 rotated 90 degrees in a counter-clockwise direction.

FIG. 5 a top plan view of the skull pan of FIG. 1.

FIG. 6 is bottom plan view of the skull pan of FIG. 1.

FIG. 7 is a side elevational view of a first side of the skull pan of FIG. 1.

FIG. 8 is an end elevational view of a first end of the skull pan of FIG. 1.

FIG. 9 is another side elevational view of a second side opposite to the first side of the skull pan of FIG. 1; and, FIG. 10 is another end elevational view of a second end opposite to the first end of the skull pan of FIG. 1.

The broken lines in the figures are directed to environment and form no part of the claimed design.
